UNITED STATES PATENT OFFICE.

CHESTER H. THORDARSON, OF CHICAGO, ILLINOIS.

ALTERNATING-CURRENT REGULATOR.

No. 921,311.

Specification of Letters Patent.

Patented May 11, 1909.

Application filed July 27, 1906. Serial No. 328,185.

To all whom it may concern:

Be it known that I, CHESTER H. THORDARSON, a citizen of the United States, of Chicago, in the county of Cook and State of Illinois, have invented certain new and useful Improvements in Alternating-Current Regulators; and I do hereby declare that the following is a full, clear, and exact description thereof, reference being had to the accompanying drawings, and to the letters of reference marked thereon, which form a part of this specification.

This invention relates to improvements in electric current regulators and refers more particularly to such regulators as are adapted by inductive impedance to regulate the current of an alternating current circuit.

Among the objects of the invention is to provide an exceedingly simple compact and efficient regulating device for this purpose and the invention consists in the matters hereinafter set forth and more particularly pointed out in the appended claims.

I have shown my regulating device as applied to an apparatus for generating X-ray lights, it being introduced into the generating circuit in a manner to act by impedance to vary the amount of current passed through the circuit and operates in such manner that the value of the current may be gradually raised or lowered and the intensity of the X-ray light generated thereby correspondingly varied. The regulating device, being shown in connection with an X-ray light apparatus will be hereinafter described in this connection and relation but it will be understood that my improvements may be employed for other regulating purposes to which it may be adapted.

Referring to the drawings:—Figure 1 is a diagram of the circuits and the essential instrumentalities included therein which go to make up an X-ray apparatus. Fig. 2 is a side elevation of one form of magnetic impedance regulator for varying the amount of current in the energizing circuit. Fig. 3 is a section taken on line 3—3 of Fig. 2. Fig. 4 is a top plan view of said device. Fig. 5 illustrates one of the plates constituting the laminated portion of the frame of said regulating device. Fig. 6 is a like view of a similar plate which goes to make up the laminated core of said regulating device.

As shown in said drawings.—A indicates a source of alternating current, B and C con-

ductors connecting said source with the primary coil E of the high potential transformer. F designates the secondary coil of said transformer, connected by conductors F¹ F¹ with the usual discharge terminals f f. 60

G designates the usual vacuum or Crookes tube, the electrodes g¹ g¹ of which are connected by conductors g² g³ with the terminal conductors F¹ F¹ of the secondary circuit of the transformer.

The impedance regulating mechanism herein shown comprises a coil H in series with the primary side of the high potential transformer, a core I which, as herein shown, is movable into and out of the coil, and a suitable frame, designated as a whole in Fig. 1 as J. The core is made of variable cross sectional area in the portion thereof which is adapted to move into and out of the coil, it being herein shown as wedge shaped or tapered from its upper to its lower or bearing surface, which latter is flat. The said regulating mechanism is shown in detail in Figs. 2 to 6, inclusive, and is made as follows:

The frame, designated by J in Fig. 1, comprises, as shown in the other figures, two side plates J¹ J¹, and an intermediate laminated body J² consisting of plates j of magnetic material (shown in detail in Fig. 5) confined between said side plates by means of traverse bolts j¹ j¹ (Figs. 2 and 4). The said side plates J¹ J¹ and the intermediate plates J² of the body are cut away to provide upwardly opening recesses, the recesses of the intermediate plates being designated as j² in Fig. 5, 90 to receive the coil H which is confined between flanges j³ extending laterally and oppositely from the side plates of said frame.

The core I slides on the upper surface of the laminated body J² into and out of the coil H, as indicated by full and dotted lines in Fig. 1. Said core is also of laminated construction, it comprising a plurality of thin plates or laminæ i of magnetic material (Figs. 3, 4 and 6), confined together between 100 side plates I¹ I¹ fixed together by means of bolts i² i² extending transversely between and through said plates. Said plates i are shown as tapered at both ends from their lower bearing surfaces to their top surfaces 105 to provide the variable area of the part of the core which moves into and out of the coil and also to provide at the other end of the core an extension adapted to be engaged by an operating part to give movement to the core. 110

The said plates may thus be cut without waste from a straight metal strip. The arrangement shown greatly simplifies the construction of the core and reduces its cost. It will be observed that the core I is in bearing contact with the laminated body of the frame J on both sides of the coil and the recess which partially receives the coil, and that said core and body have wide bearing faces. There is thus provided a closed iron path for the magnetic lines through the core and frame which greatly increases the inductive capacity of the core and this iron path is maintained throughout a large part of the range of adjustment of the core. The tapered arrangement of the core and metal to metal contacts of the core with the frame enables the current to be gradually varied within close limit, thus avoiding objectionable fluctuation or abrupt variation in the regulated current. Guide bars K K fixed to the side frames J¹ J¹, as by means of bolts k, engage upwardly opening rabbets in the side plates I¹ of the core and serve to hold the core from rising. The side plates J¹ are provided with extensions j² which support the core when the latter occupies a position withdrawn from the core. The rails K also extend outwardly over said extensions j². The means herein shown for effecting movement of the core into and out of the coil comprises a rotative shaft L mounted in a suitable bearing J³ extending laterally from one of the side plates J¹, and provided at its inner end with a pinion L¹ that engages a rack I² formed on the lower margin of one of the side members or plates I¹ of the core. Said shaft L is provided at its outer end with a hand-wheel L² by which it is rotated to advance or retract the core as desired. Means may be provided for locking the core in any position of adjustment. Means for this purpose is herein shown and consists of a locking screw M having screw-threaded engagement with a bracket J⁴ on one of the side plates of the frame and bearing at its lower end against the adjacent guide bar K, the latter for this purpose having a slight vertical movement so as to be pinched downwardly against the bottom of the rabbet occupied thereby in the plate I¹ of the core. For this purpose the aperture in said bar K, through which the adjacent fastening screw k passes, is made somewhat larger than said screw, as shown in Fig. 3.

The members of the conductor C are connected with the coil through binding screws N located at one side of the frame, near the base thereof (Figs. 2 and 3) and mounted on an insulating block N¹ affixed to said side plate.

In the operation of the apparatus, after the tube is adjusted to the apparatus and the generating circuit closed, the core I is adjusted into and out of the coil H until the

desired intensity of the ray has been attained. Thereafter the coil may be locked in position by the locking screw M.

An important advantage of the regulating mechanism herein described arises from the fact that the quantity of the current may be gradually varied within close limits, thereby producing uniform variations of the X ray effects in the tube, and free from abrupt variations. Said regulating apparatus produces particularly good results when employed in alternating current circuits, inasmuch as both the character of the current and the manner of its regulation conduce to a regular and uniform X ray effect in the tube, thereby producing a ray not only well adapted to a given or predetermined use, but also one that is free from fluctuations and deviations from a standard or desired effect.

I claim as my invention:—

1. A regulating device for alternating current apparatus comprising a coil, a frame upon which said coil is supported, and a core, the core and coil being relatively movable so as to move the core into and out of the coil, said core being of variable cross-sectional area in the part thereof which moves into and out of the coil.

2. A regulating device for alternating current apparatus comprising a coil, a frame upon which said coil is supported and a core, the core and coil being relatively movable so as to move the core into and out of the coil, said core being of variable cross-sectional area in the part thereof which moves into and out of the coil, and the core being so arranged relatively to the frame that throughout a large part its range of adjustment it completes with the frame a continuous iron path for the magnetic lines emanating therefrom.

3. A regulating device for alternating current apparatus comprising a magnetic frame provided with a transverse recess to partially receive a coil, a coil supported in said recess and a tapered core slidable on the frame into and out of the coil and arranged to have contact with the frame on both sides of said recess.

4. A regulating device for alternating current apparatus comprising a magnetic frame provided with a recess to partially receive a coil, a coil supported in said recess, a core slidable on said frame into and out of said coil and having contact with the frame on both sides of said recess, and a rack and pinion mechanism for giving movement to said core.

5. A regulating device for alternating current apparatus comprising a magnetic frame provided with an upwardly facing bearing surface and with an upwardly opening recess, a coil supported in said recess, a core supported on the upwardly facing bearing surface of the frame and movable into and

out of said coil, and guides on the frame engaging the core to prevent it rising from said frame.

6. A regulating device for alternating current apparatus comprising a magnetic frame provided with an upwardly facing bearing surface and with an upwardly opening recess, a coil supported in said recess, a core supported on the upwardly facing bearing surface of the frame and movable into and out of said coil, and an end extension on the frame arranged to support the core as it is withdrawn from the coil.

7. A regulating device for alternating current apparatus comprising a magnetic frame provided with a transverse recess to receive the coil, a coil supported in said recess and a core slideable longitudinally on the frame into and out of the coil, said core comprising a plurality of flat metal plates confined between side frames and guides on said side frames engaging parts on the magnetic frame to guide the coil into and out of the core.

8. A regulating device for alternating current apparatus comprising a magnetic frame 25 provided with a transverse recess to receive a coil, a coil supported in said recess, a core slideable longitudinally on the frame into and out of the coil, said core being of laminated construction, it comprising a plurality of flat 30 plates tapered at their ends from their bearing margins toward their opposite margins and suitably clamped together, said core being arranged to engage the frame on both sides of the recess and to maintain said engagement throughout a considerable portion 35 of range of adjustment of the core.

In testimony, that I claim the foregoing as my invention I affix my signature in presence of two witnesses, this 21st day of July A. D. 40 1906.

CHESTER H. THORDARSON.
